Application June 14, 1947, Serial No. 754,702

10 Claims. (Cl. 240—10.6)

1
This invention relates to a portable electric flashlight with retractable mount for auxiliary lamp.

Primarily the invention is concerned with a flashlight having an auxiliary extensible light.

It is an object of the invention to provide a flashlight of the character described in which the auxiliary light is normally carried in an inconspicuous retracted position but is so mounted that it can be quickly and easily moved to extended position.

It is another object of the invention to provide a flashlight of the character described in which the auxiliary light is permanently secured to the flashlight and derives its energy from the same source of electric power as does the lamp of the flashlight.

It is another object of the invention to provide a flashlight of the character described in which the auxiliary light is controlled by the same switch as that which controls the lamp of the flashlight.

It is another object of the invention to provide a flashlight of the character described having a common switch and a common source of energy for the flashlight lamp and the auxiliary light, in which the source of energy and the switch automatically supply power to and control the flashlight lamp when the auxiliary light is retracted and automatically supply power to and control the auxiliary light when the latter is moved away from its retracted position.

It is another object of the invention to provide a flashlight of the character described wherein the auxiliary light is capable of being extended from the flashlight a distance greater than the length of the flashlight itself.

It is another object of the invention to provide a flashlight of the character described in which the auxiliary light is so mounted as to be capable of a double extension, that is, a movement from retracted to an initially extended position and a further movement, which is optional with the user, from the initially extended position to yet a further extended position.

It is another object of the invention to provide a flashlight of the character described in which the auxiliary light is capable of being pointed in any direction regardless of the manner in which the flashlight is held.

It is another object of the invention to provide a flashlight of the character described which comprises relatively few and simple parts, is inexpensive to manufacture and is rugged and efficient in use.

2

Other objects of the invention will in part be obvious and in part hereinafter pointed out.

The invention accordingly consists in the features of construction, combinations of elements and arrangements of parts hereinafter described and of which the scope of application will be indicated in the appended claims.

Fig. 1 is a front view of a flashlight constructed in accordance with the invention;

Fig. 7 is a side view of the flashlight with the extension light moved far enough away from retracted position to enable the same to be energized;

25 Fig. 8 is a fragmentary side view of the flashlight with the extension light fully opened;

Fig. 9 is an enlarged view similar to Fig. 2 of the extension light and its support;

30 Fig. 10 is a sectional view taken substantially along the line 10—10 of Fig. 9;

Fig. 11 is an exploded view of a portion of the switching mechanism which automatically controls selective energization of either the flashlight lamp or the extension light; and

35 Figure 12 is a perspective partially schematic view of the electric circuit for the flashlight.

In general the several objects of this invention are achieved by modifying a flashlight of any standard design so as to incorporate therein an auxiliary light consisting of an elongated standard at one end of which the auxiliary lamp is mounted. The standard is so connected to the battery casing of the main flashlight that it can be moved between two extreme positions, in one of which, known as the "retracted position," it lies in close proximity to said casing and thereby either is substantially concealed or is inconspicuous, and in the other of which, known as the "extended position," the auxiliary light has its lamp disposed a substantial distance away from said casing. The electric circuit for the main flashlight is so modified as to provide a branch circuit for the auxiliary light, this modification being such that the auxiliary light is connected to the batteries in the main flashlight as

soon as the auxiliary light has moved a certain distance away from its retracted position. This arrangement permits the manual switch on the main flashlight to control energization both of the flashlight lamp and the auxiliary light lamp. A preferred construction is that in which the support for the auxiliary light is pivotally connected to the casing of the main flashlight whereby this support can be swung out when it is desired to employ the auxiliary light. Furthermore said support may nestably house a slideable extension piece which carries the auxiliary lamp so that after the auxiliary lamp support is swung to its extended position the sliding extension can be pulled out to further project the auxiliary lamp.

Referring now in detail to the drawings, 28 denotes a combined flashlight and extension light embodying the instant invention. The flashlight portion, as indicated above, is of conventional construction and comprises a battery casing 22 in the form of a hollow cylindrical tube 24 fabricated from a moldable insulating material, such for example as a phenolaldehyde condensate. The top of the tube is of enlarged diameter whereby to form a head portion 26, at the upper end of the flashlight. This portion is provided with a set of male threads 28 on which a head cap 30 is screwed. A lens 32 is caught between the cap and the rim of the head portion. Also held in the same manner is the flanged edge of a metal reflector 34 whose lower end has an opening therein through which the envelope of a low voltage flashlight lamp 36 extends. A ferrule 38 is crimped onto said reflector at the aforesaid opening; this ferrule being formed with suitable means, as for example, a threaded portion at its lower end, to receive internally a molded bushing 40 of insulating material. Said bushing presses the flange 42 of the lamp against a step 44 on the ferrule near the reflector. The shank of the lamp extends through the bushing and the center contact 46 of said lamp projects beneath the bottom of said bushing.

A transverse partition 48 is disposed within the casing between the tube 24 and head 26, said partition optionally, and as shown, being molded in one piece with the casing. The partition functions in the well known manner as an abutment member for the battery and as a support for various portions of the electrical system which supplies energy to the flashlight lamp. The partition additionally serves as a support for the contact assembly which determines automatically whether the flashlight lamp or the auxiliary light lamp is to be connected to the batteries.

A metal shell 50 is fastened as by riveting into the bottom end of the flashlight. Said shell is fashioned with a threaded portion which is adapted to be engaged by the matingly threaded portion of a metal cap 52 which is secured to a base cap 54. The metal cap includes a ledge 56 on which is seated the broad end of a tapering battery compression coil spring 58. This spring forces a set of batteries 60 up against the abutment partition 48.

As is usual, the circuit for energizing the flashlight lamp constitutes two legs, one running from the spring 58 to one of the terminals of the lamp, e. g. the metal sheath which covers the shank of the lamp and the other running from the central terminal of the uppermost battery 60 to the central lamp contact 46. The last mentioned leg includes a contact strip 62 which is secured to the partition 48 by suitable fastening means such as

rivets 64. A base portion 66 of the strip is held flat against the under-surface of the partition 48, said portion crossing the center of the partition in order that it may be engaged by the central terminal of the uppermost battery. The strip 62 also includes a vertical portion 68 which extends through the partition and is connected to a contact finger 70 parallel to and spaced above the top surface of the partition 48. This finger is located beneath the center of the opening in the reflector 34 and is close enough to said opening to be engaged by the center contact 46 of the flashlight lamp held in the ferrule 38. The strip 62 is of electrically conductive material and preferably is resilient, a suitable material for this purpose being Phosphor bronze.

The other leg of the electric circuit is partially shown in Fig. 4. This leg includes an electrically conductive strip 72 which is disposed longitudinally of the battery casing and lies against the side wall thereof. One end of the strip is fastened by suitable means, such as a rivet 74, to the shell 50. The other end of the strip is fastened by a rivet 76 to the molded tube 24. An intermediate portion of the strip can be held in position against the tube by another rivet 78. This rivet also is employed to fasten a manually operable switch 80 to the flashlight casing. Inasmuch as the shell of said switch is metal and is used as a part of the electric circuit, the same must be insulated from the strip 72 except when necessarily connected thereto by manipulation of the switch. For this reason the rivet 78 is spaced from the strip by a fiber washer 82.

The switch 80 includes a metal shell 84 secured to the battery casing by its lower end by the rivet 78 and at its upper end by a rivet 86. The switch casing slidably supports a button 88 in such fashion that the same can be shifted longitudinally of the flashlight. The switch casing also supports another button 90 in suitable manner to permit the same to be shifted transversely of the longitudinal axis of the flashlight. The button 88 carries a pair of fingers 92 which extend through the shell and enfold a resilient electrically conductive strip 94 having a depressed finger 96 which slides on the exterior of the battery casing. The strip 94 includes a nub 98 adapted to engage any one of a series of three indentations 100 formed on the internal surface of the switch shell. Thus, the strip 94 will be shifted with movement of the button 88 to any one of three positions which are fixed by interengagement of the nub 98 and the indentations.

When the button 88 is in its lowermost position, as shown in Fig. 4 (nearest the base cap 54) the finger 96 is in contact with the non-conductive wall of the battery casing and the tip 102 of the strip 94 is above said non-conductive wall.

When the button 88 is shifted upwardly to advance the nub 98 one indentation, the finger 96 still will remain in engagement with the non-conductive battery casing. However, the tip 102 of the strip now will be disposed in registration with, although spaced from, the externally disposed head of the rivet 76 so that if the button 90 is depressed, the strip 102, and therefore the switch shell 84, will be placed in circuit with the strip 72. Releasing the button 90 will permit the resilient strip 94 to spring back to its idle position out of contact with the rivet 76 and force said button outwardly. When the button 88 is advanced one more indentation, the finger 96 will engage the rivet 76 whereby to place the switch shell in circuit with the strip 72.

The rivet 86 which holds the upper end of the switch shell to the battery casing also serves as an electrical connector between said switch shell and an electrically conductive strip 104 located inside the battery casing. This strip extends through an opening 106 in the partition 48 and has a horizontal reach 108 held to the upper face of the partition by a rivet 110. Said rivet also serves to secure in place the base leg 112 of an electrically conductive strip having a long upright leg 114. This leg is so constructed that when unstressed it will be in such angular relationship to its base 112 that the tip 116 thereof is spaced a short distance away from the outside wall of the reflector 34. In normal operation of the flashlight, i. e. an operation which does not involve the auxiliary light hereinafter to be described, the tip 116 of said strip is forced into engagement with the reflector whereby to complete the other leg of the circuit which connects the cup electrode of the lowermost battery to the metal sheath of the flashlight lamp.

The auxiliary light is denoted by the reference numeral 120 and constitutes an elongated sleeve 122 of electrically conductive material. Said sleeve is of approximately circular cross-section but is provided with a longitudinally extending external rib 124 which forms a corresponding longitudinally extending internal groove 126. The sleeve may be fabricated from a long flat strip of sheet metal, the groove being depressed along the desired area and subsequently the longitudinal edges of the strip being curved toward one another until they meet at a seam 128. It may be pointed out here that the groove 126 extends from the upper end of the sleeve, i. e. the end near the head cap 30, to near but not up to the lower end of said sleeve.

The upper end of the sleeve includes flattened side portions 130 of circular contour which are provided with registered apertures 132 to receive a pin 134 on which the sleeve is journaled. The opposite ends of the pin are secured in a pair of ears 136 which may be molded integrally with the battery casing. It thus will be appreciated that the sleeve 122 can be swung through 180° from a retracted position in which it lies flat against the side of the battery casing and runs along the length thereof, as shown in Fig. 2, to an extended position in which it is parallel to the battery casing but projects forwardly therefrom, as shown in Fig. 8. Due to the enlarged diameter of the head portion 26, it is desirable to offset the pin 134 so that the sleeve in its retracted position may lie alongside of the casing and in its extended position lie alongside of the head. The amount of offset is one-half the difference in radii of the battery casing and head portion, the displacement being outwardly from the center line of the sleeve in its retracted position.

The sleeve carries an auxiliary extension lamp in the form of a conventional light bulb 138 of the type having an envelope with an integral lens. Said bulb is held in place in a certain manner, hereinafter described in detail, the threaded shell 140 thereof being in series with the sleeve 122 and the center contact 142 of the lamp being in series with an electrically conductive insulated wire 144.

Pursuant to the invention means is provided which is operative upon movement of the sleeve 122 toward extended position to disconnect the flashlight lamp 36 from the circuit controlled by the switch 80 and to connect the auxiliary lamp

138 in said circuit. Said means preferably is constructed so that the auxiliary lamp is automatically thrown into circuit after it has moved a predetermined angular distance away from its closed position and desirably the means is so constructed that as the sleeve passes through this position, or within a short angular distance before or after said position, the flashlight lamp is cut out of circuit.

10 The foregoing means constitutes a pair of discs 146, 148 of insulating material provided with central apertures 150 in which the pin 134 is freely rotatable. The disc 148 has a peripheral notch 152 in which a transverse strip 154 of insulating material integral with the other disc 146 is received. This strip includes a camming portion 156 which extends radially away from the discs.

15 The disc 146 is partially covered by an electrically conductive cap 160 having a flat base wall 160 which lies on the outer side face of the disc 146 and a rim 162 which extends around the periphery of the disc and runs from the covered side face of said disc toward but not to said inner face. Said base wall 160 has an opening 164 which snugly receives a projection 165 on one of the flat side portions 130. Said projection also is snugly fitted into an opening 166 extending through the disc 146. The rim 162 has a notch 30 168 therein to pass the camming portion 156. The base wall 160 is provided with a central opening 170 to rotatably receive the pin 134.

20 The other disc 148 likewise is partially covered by an electrically conductive cap 172 having a flat base wall 174 which lies on the inner face of the disc 148 and has a rim 176 encircling the periphery of said disc. This rim extends toward but not up to the outer face of the disc 148 and is notched as at 178 to pass the camming portion 40 156. The base wall 174 includes an oversized central aperture 180 through which the pin 134 extends but does not touch. Said base fall also has an outwardly extending projection 182 which is received in the opening 165 but is disposed on the opposite side of the disc 146 from that on which the projection 164 is located. The cap 172 includes a lug 184 which is suitably electrically connected to the wire 144, as for example by solder 186.

25 It will be appreciated that the transverse strip 154 and projections 165, 182 will cause the sleeve 122 and both discs and caps to turn together.

30 The heads of the pin 134 press the ears 136 against the flat side portions 130 of the sleeve 122 whereby to frictionally retain the sleeve in any angular position to which it may be turned.

35 The camming portion 156 is so located with respect to the sleeve 122 that when the latter is in its restricted position shown in Fig. 2 said portion causes the tip 116 of the upright conductive leg 114 to be pressed against the flashlight reflector 34. The camming portion need not directly engage the leg 114 but, as shown, may press against the upright tip 188 of an electrically conductive strip 189 whose base portion 190 is held to the partition 48 by the rivet 110. Inasmuch as this is the same rivet as that employed to hold the leg 114 in position, the two base portions 112, 190 are both in electrical connection with the strip 104 whose energization is controlled by the switch 80. Said tip 188 is disposed at the end of an offset 192 extending outwardly from the upper end of the shank 194 of the strip 189. The shank 194 is located on the 45 outer side of the upright leg 114 and, when un-

stressed, merely lies alongside said leg. However, when the tip 188 of the strip 189 is moved inwardly by the camming portion 156, said strip will press the leg 114 inwardly, the camming portion being of such dimensions and so oriented that when the sleeve 122 is in retracted position it will press the tip 188 in far enough to cause the tip 116 of the leg 114 to engage the reflector 34.

It will be appreciated that with this arrangement if the sleeve 122 is revolved through a small angle away from its retracted position the camming portion 156 will become disengaged from the tip 188 of the strip 189. Said strip thereupon will return to its normal position in which it engages the conductive cap 158 so that said cap is prepared to be energized by proper manipulation of the switch 30. Thus the strips 114, 189 jointly act as the throw member of what, in effect, is a single pole, double throw switch which in one position closes a circuit from the battery to the lamp 36 and in the other position to the lamp 138.

When the sleeve is in an outward position, the other cap 172 is engaged by the tip 196 of an electrically conductive strip 198 whose base 200 is secured to the partition 48 by the rivet 64 so that said strip 198 is permanently electrically connected to the central terminal of the uppermost battery 60. The base 200 of said strip is attached to the tip 196 thereof through a shank 202 and offset portion 204.

The tips 188 and 196 of the strips 189, 198 respectively, are aligned so that both said tips will simultaneously be engaged in like manner by the camming portion 156.

As already noted, engagement of the camming portion with the strip 189 serves to disengage said strip from the cap 158. Similarly the engagement of the camming portion with the strip 198 will disengage the latter strip from the cap 172 which it normally engages when the camming portion is out of the way. Thus rotation of the sleeve into such position that the camming portion abuts the tips of the two conductive strips will cause said strips to break contact with the two caps 158, 172 and open both legs of the electric circuit to the auxiliary extension lamp.

It further will be noted that the camming portion presses the tip 116 against the reflector 34 at substantially the same angular position of the discs as that at which said camming portion disengages the strip 189 from the cap 158 so that the main flashlight lamp 36 is rendered energizable at about the same position of the sleeve 122 as that at which the auxiliary flashlight lamp is cut out of circuit, and vice versa.

It should be noted that the reason both legs of the circuit to the auxiliary flashlight lamp are broken when said lamp is in retracted position, is to prevent accidental energization of said lamp should a circuit accidentally be established bridging the switch shell and the sleeve 122. This circuit would bypass the switch comprising the cap 158 and strip 189. However, with the other leg of the circuit opened by breaking the contact between the strip 198 and cap 172, the auxiliary extension lamp cannot be energized accidentally.

If desired, the switch which controls the connection to the batteries of the lamp 138, or any other switch of suitable construction, may control the connection to the batteries of a fixed auxiliary lamp or lamps or even of some other power consuming auxiliary (e. g. a fuse tester) rather than the movable auxiliary lamp as indicated. Such fixed lamp or lamps or other auxil-

iary can be secured in any convenient manner upon or within the casing.

Means is provided to aid in locating and at least partially concealing the auxiliary extension when the same is in retracted position, such means comprising a channel defined by two spaced flanges 206, 208 which are molded integrally with the casing. Said flanges run parallel to one another and extend along the length of the battery casing, being sufficiently high to receive a substantial portion of the sleeve 122 when the latter is folded up to lie flat against the casing. Each of the flanges has a crescent shaped cutout 210 which allows a user to grasp the sleeve with his fingers in order to extend the same. The foregoing channel constitutes in effect a receptacle integral with and on the exterior of the casing. Such receptacle may if desired be modified in size and shape to receive and house an auxiliary member other than the pivoted light. For instance it could house a separate small flashlight which is completely removable from the flashlight 20 and has its own source of energy. Said separate flashlight would be held in place in the receptacle by suitable clips.

Means also may be included to secure the extension in retracted position so that it only can be opened deliberately. Said means is in the form of a clip 212 of resilient material, such as spring steel, shaped to resiliently clasp the end of the sleeve 122 remote from the pin 134. The clip is held in position by a rivet passing through the side wall of the battery casing.

In order to allow for greater extension of the lamp, for instance into holes or pipes, or within curved narrow spaces, the auxiliary lamp 138 instead of being mounted in a socket fixedly secured to the swinging end of the sleeve 122 is carried by a metal socket 214 which is secured to one end of a flexible conduit 216 which easily is manually deformable. A suitable conduit is one formed from convoluted metal strips such as are used to shield electric wires. The other end of the flexible conduit is received in a slide fitting 218, constituting a metal cup 220 having a base 222 with an aperture therein through which the insulated wire 144 extends and is caught. The rim of the cup has several, e. g. six, narrow fingers 224 integrally formed thereon. These fingers when unstressed flare outwardly at a slight angle to the sides of the cup, for instance about 15°. The cup is formed of a resilient electrically conductive material, for example, Phosphor bronze. The bases of the fingers are offset outwardly a slight distance from the rim of the cup and conjointly define a circle of substantially the same diameter as the bore of the sleeve 122. Thus, said cup may be slid longitudinally of the sleeve and will frictionally engage the interior of the sleeve in any given position whereby to hold itself and the flexible conduit 216 which is connected thereto in the position in which it is left.

The cup is prevented from rotating by entry of one of the fingers into the groove 126 as shown in Figs. 9 and 10. Engagement between this finger and the groove also stops the cup from being slid out of the open end of the tube inasmuch as said finger is limited in its movement by abutment thereof against a step 226 constituting the lower end of the groove 126. This arrangement does not prevent easy assembly of the cup and sleeve because said cup can be introduced 75 into the sleeve simply by thrusting the same into

the open lower end of the sleeve. Such action will cause all of the spring fingers to be constricted until the cup has passed the mouth of the sleeve. When the cup is pushed wholly into the sleeve it can be turned until one of the fingers 5 springs into the groove 126.

The flexible conduit 216 is electrically conductive and is held in place in the cup as for example by solder 228. The other end of the flexible conduit is received in a pocket 230 integral with the socket 214 and is secured in place in a suitable fashion, as for instance by solder 232. Thus the shell of the lamp 138 always is in electric circuit with the sleeve 122 which in turn is constantly electrically connected to the cap 158. 15

The electric connection for the central contact 142 of the flashlight extension lamp is made through the wire 144. Said wire is insulated and, as already noted, extends through an opening in the base of the cup 213. From here the wire 20 passes through the flexible conduit 216 and ends at a central terminal 234 located within the socket 214. Said terminal, as illustrated, is insulated from the socket.

It thus will be appreciated that the cup 218 can be slid along the length of the sleeve 122 and in any position thereof the lamp 138 can be energized, providing, of course, that the sleeve 122 has been swung out far enough to permit the strip 189 to engage the cup 158.

Although the same is in no sense to be considered as constituting a limitation upon the invention, it may be mentioned, by way of example, that the auxiliary extension light is particularly useful where it becomes effective only a short distance after it has been swung away from the battery casing, e. g. through as little as 10°, inasmuch as under these circumstances light can be cast even on a member on which the flashlight is standing and which it is desired to illuminate.

The wire 144 is made sufficiently long so that when the cup is in its most extended position shown, for example in Fig. 8, said wire will easily span the distance from the cup to the lug 184. Moreover, in order that said wire may occupy a minimum space at such time as the flexible extension 216 is retracted, and to avoid kinking of the wire which may lead to breakage thereof, said wire has a set imparted thereto, the set being such that the wire will normally assume a closed helical shape such as indicated in Fig. 9. When the wire is expanded it will assume the position shown in Fig. 8; but at such time as the flexible conduit is retracted into the sleeve, the wire will automatically reassume its closely compacted helical formation. The desired set can be imparted to the wire rather simply, as for instance merely by winding the wire in a close helix about a mandrel having a diameter slightly less than the internal diameter which the set wire is to take. Ordinary insulated copper wire thereupon will retain this configuration when stretched only to the extent indicated in Fig. 8.

A transparent or translucent guard may be employed to protect the envelope of the lamp 138 when the same is in closed or intermediate positions and also when the same is employed in close quarters. Said guard conveniently is manufactured from a transparent or translucent synthetic resin plastic, such for instance as cellulose acetate butyrate or a styrene resin. The guard includes a cylindrical portion 236 having a diameter slightly greater than the outer diameter of the socket 214 so that it easily can be slid over the same. The forward portion 238 of the guard is of re-

duced diameter, being adapted to be received over the envelope of the lamp and to permit the tip of the envelope only to extend therethrough. The back of the guard has an inturned integral flange 240 which is adapted to be disposed in back of a step 242 on the socket 214 whereby to lock the guard in place. The guard is secured on the lamp merely by placing the same over the lamp and pushing it toward the pin 134. If the guard is thin enough, it will yield sufficiently to permit the flange 240 to expand far enough to be slid over the socket 214. However, if as is shown herein, the walls of the guard are too thick to permit of such expansion, at least one longitudinal slot 242 can be provided in the guard to enable the flange 240 to be spread to the required extent.

It will thus be seen that there is provided a flashlight which achieves the several objects of the invention and is well adapted to meet the conditions of practical use.

As various possible embodiments might be made of the above invention and as various changes might be made in the embodiment above set forth, it is to be understood that all matter herein described or shown in the accompanying drawings is to be interpreted as illustrative and not in a limiting sense.

I claim:

1. A portable electric flashlight comprising in combination a casing including a head and an elongated portion adapted to house batteries, a flashlight lamp in said head, circuit means to energize said lamp from said batteries, said means including an electric switch operable externally of the casing, and an auxiliary extensible light, said light including an elongated standard, means to pivotally mount said standard adjacent an end of said casing for swinging movement relative to the head and battery portion in a plane including the longitudinal axis of the battery housing portion from a position in which the standard lies flat against the casing to a position in which the standard extends from the casing, an elongated self - form - maintaining member slidable in said standard from a position in which it is substantially fully received in the standard to a position in which it is substantially fully extended from the standard, an auxiliary electric lamp carried by said elongated member, and circuit means for energizing said auxiliary lamp from said batteries.

2. A portable electric flashlight comprising in combination a casing including a head and an elongated portion adapted to house batteries, a flashlight lamp in said head, circuit means to energize said lamp from said batteries, said means including an electric switch operable externally of the casing, and an auxiliary extensible light, said light including an elongated standard, means to pivotally mount said standard adjacent an end of said casing for swinging movement relative to the head and battery portion in a plane including the longitudinal axis of the battery housing portion from a position in which the standard lies flat against the casing to a position in which the standard extends from the casing, an elongated self-form-maintaining manually distortable member slidable in said standard from a position in which it is substantially fully received in the standard to a position in which it is substantially fully extended from the standard, an auxiliary electric lamp carried by said elongated member, and circuit means for energizing said auxiliary lamp from said batteries.

3. A portable electric flashlight comprising in

combination a casing including a head and a portion adapted to house batteries, a flashlight lamp in said head, circuit means to energize said lamp from said batteries, an auxiliary extensible light, said light including an elongated standard, an auxiliary electric lamp carried by said standard, circuit means for energizing said auxiliary lamp from said batteries an electric switch operable externally of the casing and common to both circuit means, means to retractably mount said standard on said casing, a single pole double throw switch means common to both circuit means and adapted to render either one or the other of the circuit means effective, and an element movable with the standard and operable upon movement thereof to actuate the single pole double throw switch means in such manner that the second named circuit means is rendered effective when the standard is moved a predetermined distance away from retracted position and the first named circuit means is rendered effective when the standard is in retracted position.

4. A portable electric flashlight comprising in combination a casing including a head and a portion adapted to house batteries, a flashlight lamp in said head, circuit means to energize said lamp from said batteries, an auxiliary extensible light, said light including an elongated standard, an auxiliary electric lamp carried by said standard, circuit means for energizing said auxiliary lamp from said batteries an electric switch operable externally of the casing and common to both circuit means, means to retractably mount said standard on said casing, a single pole double throw switch means common to both circuit means and adapted to render one or the other of said circuit means effective, said single pole double throw switch means including a first contact member forming part of the first named circuit means, a second contact member forming part of the second named circuit means and movable with the standard, and a throw member, and means moved by said standard to actuate the throw member.

5. A portable electric flashlight comprising in combination a casing including a head and a portion adapted to house batteries, a flashlight lamp in said head, circuit means to energize said lamp from said batteries, an auxiliary extensible light, said light including an elongated standard, an auxiliary electric lamp carried by said standard, circuit means for energizing said auxiliary lamp from said batteries, an electric switch operable externally of the casing and common to both circuit means, means to pivotally mount said standard on said casing, a switch means for selectively energizing one or the other of the circuit means, said switch means including a throw member, a contact member on said battery casing and forming part of the first named circuit means, a contact member rotatable with the standard and forming part of the second named circuit means, and a camming member carried by the standard and engaging the throw member, said camming member being so shaped as to cause the throw member to engage the first named contact member when the standard is in retracted position against the battery casing and to engage the second named contact member when the standard is moved away from retracted position.

6. A portable electric flashlight comprising in combination a casing including a head and a portion adapted to house batteries, a flashlight lamp in said head, circuit means to energize said lamp from said batteries, an auxiliary ex-

tensible light, said light including an elongated standard, an auxiliary electric lamp carried by said standard, circuit means for energizing said auxiliary lamp from said batteries, an electric switch operable externally of the casing and common to both circuit means, means to pivotally mount said standard on said casing, switch means to selectively render one or the other of the circuit means effective, said switch means including a throw member near the pivotal mounting means, a contact member on the battery casing and forming part of the first named circuit means, a second contact member carried by the standard and forming part of the second named circuit means, said second contact member being of circular configuration and concentric with the pivotal axis, means to bias said throw member against said contact member and a camming element carried by the standard and arranged to press the throw member away from the second contact member and into engagement with the first contact member when the standard is in retracted position flat against the battery casing, said camming member being disengaged from said throw member when the standard is moved away from retracted position whereby the throw member can engage the second contact member to render the second named circuit means effective when the standard is moved away from retracted position.

7. For use in a portable electric flashlight having a flashlight lamp and an auxiliary electric lamp which are both adapted to be energized from the same battery and in which the auxiliary lamp is carried by a member pivotally mounted on a casing for the battery: a switch means comprising a throw member, a contact member on the casing and a contact member carried by the pivotally mounted member, the second named contact member having a circular configuration concentric with the axis of rotation of the pivotally mounted member, a camming member carried by the pivotally mounted member, the throw member being biased toward the second contact member and the camming member being so shaped and arranged that in one position of the pivotally mounted member it will press the throw member against the first named contact member and in another position of the pivotally mounted member it will release its pressure against the throw member so that the latter may engage the second named contact member.

8. A portable electric flashlight comprising in combination a casing including a head and a portion adapted to house batteries, a reflector in said head, a flashlight lamp carried by said reflector, means to effect an electrical connection from the center terminal of the uppermost battery in the casing to the center contact of the flashlight lamp, an elongated standard, an auxiliary electric lamp carried by said standard, means to mount said standard for pivotal movement on said casing, a pair of discs of electrically non-conductive material rotatable with said standard about the axis of pivotal movement thereof, each of said discs having a cap of electrically conductive material, said caps being insulated from one another by said discs, a pair of throw members biased into engagement with said caps, a camming element rotatable with said standard and engaging said throw members when said standard is in retracted position against the casing whereby to disengage said throw members from said caps in such position of the standard, one of said throw members in the aforesaid position of the standard being pressed into engagement with the re-

reflector, circuit means connecting the two caps to the auxiliary electric lamp, means to connect the other throw member to the central terminal of the uppermost battery, means to connect the cup terminal of the lowermost battery to the throw member which is adapted to engage the reflector, and an electric switch operable externally of the casing and series connected in said last means.

9. A portable electric flashlight comprising in combination a casing including a head and a portion adapted to house batteries, an elongated standard, means to pivotally mount one end of said standard adjacent an end of said casing for swinging movement relative to the head and battery portion from a position in which the standard lies flat against the casing to a position in which the standard extends from the casing, a flexible conduit slidable in said standard from a position in which it is substantially fully received in the standard to a position in which it is substantially fully extended from the standard, an electric lamp carried by said conduit, and circuit means to energize said lamp from said batteries.

10. A portable electric flashlight comprising in combination a casing including a head and a portion adapted to house batteries, an elongated standard having an internal groove running

longitudinally thereof, means to pivotally mount said standard on said casing, a member slidable within said casing, said member having an element riding in said groove, means to resiliently press said element into said groove, a flexible conduit having one end thereof secured to said member, and an electric lamp carried at the other end of said conduit.

BERNARD FRANCIS MULDOON.
